UNITED STATES PATENT OFFICE.

JAMES A. KINNEY, OF LEBANON, PENNSYLVANIA, ASSIGNOR TO BETHLEHEM STEEL COMPANY, OF BETHLEHEM, PENNSYLVANIA, A CORPORATION OF PENNSYLVANIA.

BOLT POINTING AND THREADING MACHINE.

Application filed June 13, 1923. Serial No. 645,186.

The present invention relates to bolt pointing and threading machines, and particularly to machines designed and constructed for pointing and threading relatively long bolt blanks.

One object of the invention is to provide a machine of this character having a plurality of bolt pointing and threading units positioned side by side and driven from a common power source, the various units being connected to the power source in such manner that they operate in timed relationship, permitting one operator to handle a considerable number of units. Immediately after placing the bolt blank upon one unit a finished bolt is delivered by another unit and the units between these extremes have progressed to different stages in their pointing and threading operations, the movements of the various units being so timed that a single operator is enabled to keep them all actively at work by removing the completed bolts and supplying fresh blanks.

The invention embodies a considerable number of novel features which will be described in the specification and particularly pointed out in the claims. Each unit includes a novel bolt pointing mechanism provided with means for regulating the exact amount to be removed from the end of a bolt in the pointing operation, and each unit includes novel means for effecting relative movement of the bolt blank holding member and the threading die, which means effects relative movement of these members to bring the end of the bolt blank into engagement with the die but which thereafter becomes inactive to effect further movement of these members toward each other, permitting the blank to move into the threading die solely by the action of the die upon the blank in forming threads. Undue axial pressure on the blank, resulting in side pressure on the threads being formed, is thus avoided. The operation of the threading and pointing mechanism of each unit is brought about by a novel arrangement of mechanical elements.

One embodiment of the invention is disclosed in order that the invention may be fully understood but it will be obvious that the design and arrangement of the component elements may be considerably modified without departing from the spirit of the in-

vention and that this embodiment is advanced by way of example only.

In the drawings:

Figure 1 is a plan view of the machine, certain of the intermediate units being omitted;

Figure 2 is an end elevation of the same as seen from the right, (Figure 1);

Figure 3 is a side elevation as seen from the top (Figure 1);

Figure 4 is a vertical section through the machine taken along the axis of one of the pointing and threading units;

Figure 5 is a view similar to Figure 4, a portion of the mechanism being omitted however, and certain operative parts being shown in different positions; and

Figure 6 is a view similar to Figure 5 showing the parts in still other positions.

The machine is supported upon a bed or table 10 provided with legs 11 and the frame includes a box-like member 12 bolted to the bed, and the forwardly extending bracket 75 portion 13. A power shaft 14, arranged parallel to the box-like supporting member 12, and supported in bearings 15 secured to this member has a plurality of bevel gears 16 fixed thereon, which mesh respectively with bevel gears 17 on short shafts 18 disposed at right angles to the shaft 14. Rotary motion of each shaft 18 is communicated to two spindles 19, one of which lies on each side of this shaft, through gears 20 and 21. The spindles 19 rotate the threading dies and the pointing tools and it will thus be seen that these members rotate constantly so long as the power shaft 14 is driven by any suitable means, as for instance by means of a belt arranged on pulley 22. Each spindle 19 is rotatably supported in spaced bearings 23 bolted or secured to the top of the box-like supporting member 12. This supporting member 12 has the central portion of its top removed to receive gears 21 and other moving parts of the mechanism and it also has its bottom apertured to accommodate certain other moving parts. The several bolt pointing and threading units are similar in design and construction, although timed to operate in sequence, and it will be necessary to describe in detail one such unit only, to render the operation of all apparent.

Each spindle 19 is provided with a friction clutch 25 between its driving gear 21 and the 105 threading die 26 secured to its forward end

so that a single unit may be disconnected at will without interfering with the continued operation of the other spindles. This threading die is preferably of the type disclosed in my copending application Serial No. 609,041, filed December 26, 1922, and is provided with threading jaws which are moved to closed or threading position by the movement of the conical operating member 27 into the die, and 10 are allowed to open by a movement of this member in the reverse direction.

The bolt pointing tool is indicated at 28 and comprises a long rod provided with cutting edges on its forward end, which rod extends through an axial aperture in the spindle 19 and is considerably longer than the spindle. The rod 28 is movable axially of the spindle and is rotatable therewith, being splined to the spindle for this purpose, or 20 preferably having a squared portion intermediate its ends slidably engaging a correspondingly squared aperture in the spindle.

To the forward end of the bracket 13 is secured a slide rest 30 which supports the bolt blank holding slide 31 for movement parallel to the axis of the spindle. The slide 31 has secured thereon the bolt head holding member 32 and the bolt shank supporting member 33. The member 32 is provided with 30 a recess 34 into which the head of a bolt blank may be inserted, the flat sides of the head lying close to the lateral walls of the notch so that the bolt blank cannot rotate when undergoing the threading operation. The slide 31 is provided with a downwardly extending flange or lug 31^a which is secured to a hollow rod member 35 extending horizontally and parallel to the axis of the spindle. The rear end of rod member 35 is pivotally secured to 40 the upper end of a bell crank lever 36, the end of this lever being bifurcated and which lever is pivotally supported upon an axle 37 mounted in the frame. The lower arm of bell crank lever 36 is received within a recess 38 in a lever 39 also pivoted on axle 37 and provided with weights 40 adjustably mounted on its opposite end. The weighted lever 39 normally tends to rotate bell crank lever 36 in a clockwise direction and constitutes a means 45 to bias or draw the slide 31 toward the threading die. An adjustable stop 41 limits the downward movement of the lever 39 (but not the movement of bell crank lever 36).

The die opening and closing cone 27 is provided with a rearward extension having an annular slot 43 and into this slot extend coaxial pins 44 secured to the spaced upper end portions of a lever 45 (which is bifurcated) pivoted at 46 to a bracket secured to the frame. 55 A collar 47 adjustably secured on rod 35 is adapted to strike the curved projection 48 on lever 45 when the slide 31 is thrust forwardly or away from the threading die, to cause the jaws of the die to close for a succeeding threading operation. Pivoted to lever 45

at approximately its mid-point is a link 49 having threaded on its rear end abutment nuts 50. This link slidably extends through an apertured block 51 pivotally secured to the upper end of a lever 52, also journaled or pivotally supported on the axle 37. Extending through the axial aperture in the rod 35 and having threaded engagement with said rod at some point along its length, preferably at its rear end, is an adjusting rod X, the rear end of which is adapted to engage the lever 52 at a certain time in the operation of the machine. This rod may be adjusted to determine the length of the portion of the bolt blank to be removed by the pointing tool, in 80 a manner hereinafter to be pointed out.

The levers 36 and 52 are provided with rollers 53, 54 respectively which are positioned to engage cams mounted upon shaft 55 for rotation therewith. A short cam 56 (measured circumferentially) is adapted to engage roller 53 and roller 54 extends within a cam groove 57 in cam plate or disk 58. Rotation of the shaft 55 therefore effects movement of levers 36 and 52 but it will be observed that while the lever 52 is positively operated in both directions as shaft 55 moves in a clockwise direction (Figure 4), lever 36 is positively operated in only one direction, that is, toward the front of the machine. The return movement of this lever is brought about in part by the weighted lever 39 and in part by the action of the threading die 26 on the bolt blank, drawing the bolt blank toward the right (Figure 4) or toward the rear of the machine and causing movement of the slide 31, rod 35 and lever 36 in the same direction.

Fixed upon the rear end of the pointing tool 28 so as to be movable therewith in an axial direction but non-rotatable, that is, permitting free rotation of the pointing tool within the same, is a collar 60 provided with horizontal oppositely extending pins 61 which are received within notches 62 in the spaced upper end portions of the two part lever L, which is pivoted at 63 to a bracket secured to the frame of the machine. As can be seen clearly from Figure 2, the upper portion or link 64 of lever L is bifurcated and is provided with a transverse web 65 while the lower portion 66, which is pivotally secured to the upper portion by a bolt 67, is provided with an extension 68 (Figure 5) which is normally pressed against the underside of the web 65 by means of a coiled spring 69 confined between an abutment 70 resting against web 65 and an abutment plate 71 adjustably mounted on the outer end of the short column 72 pivoted at 73 to the extension 68. The spring 69 tends to yieldingly maintain the upper and lower portions of lever L in alignment as shown in Figure 4, but permits movement of the upper portion of the lever relatively to the lower portion about the pivot 130

bolt 67 in a clockwise direction (Figure 4). A link 75 pivotally connects the bolt 67 to the lever 52 so that these members move in unison in the operation of the machine. As is obvious, the lower member 66 of lever L may be considered to be a lever actuated by link 75, the upper member 64 being a link connection between lever 66 and the pointer member.

10 The cam shaft 55 is driven from power shaft 14 through gear train G, clearly shown in Figures 2 and 3 and which includes beveled gears 77, worm 78 and worm gear 78^a mounted on the end of this shaft.

15 In the operation of one of the units a blank is first positioned on the slide 31, assuming the slide to be in its outer or forward position as shown in Figure 4. The pointing tool and threading die are in rapid rotation 20 and the cam shaft 55 is moving in a clockwise direction, although at much slower speed. The end of the pointing tool is projecting beyond the face of the cutting die. As soon as the cam 56 disengages roller 53

25 the weighted lever 39 acts to draw the slide 31 to the right and this movement is uninterrupted until the end of the bolt blank strikes the end of the pointing tool. The action of weights 40 overcomes the action of

30 spring 69 and the upper end of lever L or link 64 is pushed rearwardly by the pressure of the bolt blank on the pointing tool, as shown in Figure 5, link 75 preventing rearward movement of the lower portion of lever

35 L and roller 54 preventing substantial rearward movement of lever 52. In Figure 4 the slide 31 is just about to start rearwardly and rearward motion continues until the rear end of the adjusting rod X strikes the lever

40 52. Rearward movement of the blank is thus temporarily halted before its end has entered the die and spring 69, which has been compressed (Figure 5) and which constantly tends to expand, feeds the pointing tool forward to effect the trimming of the bolt point. Continued rotation of the cam 58 results, after it has turned through substantially 180°, in rearward motion of the lever 52 and lever L so that the pointing tool is rapidly drawn within the threading die. During

45 this rearward movement the levers 36 and 52 move together, the weighted lever 39 pressing the end of the rod X against the lever 52. Although levers 36, 52, and L move synchronously, the movement of the pointer is more rapid than that of the blank holder because of lever L being longer than the lever arm of lever 36.

50 The threading die is closed and the bolt blank enters the same. Immediately thereafter the weighted lever 39 engages the stop 41 and further movement of the bolt blank into the threading die is caused by the action of the die on the blank and without other forces being exerted to effect this movement.

Threading of the bolt blank continues until the block 51 strikes the abutment nut 50 on the end of the link 49 resulting in the movement of the lever 45 to the right and the withdrawal of the die closing cone 27 from the die, 70 thereby allowing the jaws to open. After the die jaws are opened the slide 31 becomes stationary and will remain stationary until the cam 56 again engages the roller 53, when the slide is returned to its forward or outermost 75 position.

In Figure 6 the parts are illustrated in the positions which they occupy immediately after the threading and pointing of the bolt and just as the slide is beginning to move to 80 its outermost position. By adjusting the rod X so that the movement of the slide in a rearward direction is halted at the desired position by contact of the inner end of the rod X with the lever 52, the extent of the rearward 85 movement of the upper portion of the lever L and the length to be cut from the end of the bolt cutter is regulated. The bolt pointing is entirely accomplished before the blank enters the threading die, the spring 69 holding the 90 pointing tool against the blank while the slide 31 is stationary—the spring expanding as the end of the blank is cut away. The pointing is completed when the two portions of lever L are again in alignment, and the operation of 95 the mechanism is so timed that immediately after pointing levers 36 and 52 move rearwardly and threading is begun. The pointing tool moves rearwardly at a much faster rate than the slide and does not obstruct the 100 passage of the bolt blank into the die.

The various units of the machine operate in timed relation to each other so that bolts are completed successively thereby enabling a single operator to pass from unit to unit and to remove from each in succession a finished bolt as it is completed, and to insert a blank. The machine is particularly adapted for use with bolts of considerable length, but to one skilled in the art it will be obvious that it may be adapted for bolts of shorter length and also that the design and arrangement of the component elements of the invention may be considerably changed without departing from its scope.

110 Having thus described the invention what is claimed as new and desired to be secured by Letters Patent is:

1. In a threading and pointing machine, the combination of a threading die; a pointer member; a blank holder; means for traversing the blank holder including a rod, a lever pivotally connected to the rod, a cam effective during a fraction of its rotation to swing the lever in one direction, and biasing means to swing the lever in the other direction; means for traversing the pointer member including a cam, a first lever having a follower engaging the cam, a second lever, a link connecting the levers, and yieldable connecting means be- 115
120
125
130

tween the second lever and the pointer member to permit over-travel of the latter in one direction with respect to the second lever; and means for opening and closing the die including an operating member, a lever connected to the operating member, an abutment carried by the rod of the blank holder traversing means for moving the lever in one direction to move the operating member to close the die, and means operated by the pointer member traversing mechanism at a predetermined position of the latter to move the lever in the other direction to open the die.

2. In a threading and pointing machine, the combination of a blank holder; a pointer member; a threading die; means for traversing the blank holder including a cam effective during a portion of its rotation to move the blank holder in an outward direction and means for biasing the blank holder for movement in an inward direction; means for traversing the pointer member including a cam, mechanism operated by the cam, connecting means between the mechanism and the pointer member including a yieldable member which is overcome by the blank holder biasing means when a blank contacts with the pointer member, whereby the blank holder, the blank, and the pointer member move together relatively to said mechanism, and means carried by the blank holder traversing means and by said mechanism for rendering the biasing means ineffective to secure relative movement of the pointer member with respect to said mechanism, whereupon the yieldable member becomes effective as the sole means to advance the pointer member as the blank is being pointed; means for opening and closing the die including an operating member, means operated by the traversing mechanism of the blank holder during the extreme portion of the outward movement of the blank holder for rendering said operating member effective to close the die, and means rendered effective when said mechanism of the pointer member traversing means occupies a predetermined position to render said operating member effective to open the die.

3. In a threading and pointing machine, the combination of a blank holder; a pointer member; a threading die; means for traversing the blank holder including a cam effective during a portion of its rotation to move the blank holder in an outward direction and means for biasing the blank holder for movement in an inward direction; means for traversing the pointer member including a cam, mechanism operated by the cam, connecting means between the mechanism and the pointer member including a yieldable member which is overcome by the blank holder biasing means when a blank contacts with the pointer member, whereby the blank holder, the blank, and the pointer member move together relatively to said mechanism, and adjustable

means carried by the blank holder traversing means and by said mechanism for rendering the biasing means ineffective to secure relative movement of the pointer member with respect to said mechanism, whereupon the yieldable member becomes effective as the sole means to advance the pointer member as the blank is being pointed; means for opening and closing the die including an operating member, means operated by the traversing mechanism of the blank holder during the extreme portion of the outward movement of the blank holder for rendering said operating member effective to close the die, and means rendered effective when said mechanism of the pointer member traversing means occupies a predetermined position to render said operating member effective to open the die.

4. In a threading and pointing machine, the combination of a blank holder for blanks to be threaded; a pointer member; a threading die; means for traversing the blank holder including a cam effective during a portion of its rotation to move the blank holder outwardly, biasing means for moving the blank holder inwardly, means for rendering the biasing means ineffective to secure inward movement of the blank holder after a blank is engaged by the threading die; means for traversing the pointer member including a cam, mechanism operated by the cam, connecting means between the mechanism and the pointer member including a yieldable member which is overcome by the blank holder biasing means when a blank contacts with the pointer member, whereby the blank holder, blank, and pointer member move together relatively to said mechanism, and means carried by the blank holder traversing means and by said mechanism for rendering the biasing means ineffective to secure movement of the pointer member relatively to said mechanism, whereupon said yieldable member is effective as the sole means to advance the pointer member as the blank is being pointed and said biasing means is effective to cause the blank holder and the blank to follow the motion of said mechanism; means for opening and closing the die including an operating member, means rendered effective during the outward portion of the outward movement of the blank holder traversing means to render the operating member effective to close the die, and means rendered effective when said mechanism of the pointer member traversing means reaches a predetermined position to render the operating member effective to open the die.

5. In a threading and pointing machine, the combination of a blank holder for blanks to be threaded; a pointer member; a threading die; means for traversing the blank holder including a peripheral cam having a cam portion of limited arcuate extent, a lever having a portion arranged in the path of movement

- of said cam, a rod connected to the blank holder and pivotally connected to the lever, weight means cooperating with said lever to cause the latter to move inwardly toward the 5 cam, means for limiting the range of effectiveness of said weight means; means for traversing the pointer member including a face cam coaxial with the first cam and having a cam groove in one face thereof, a first lever having its pivot coaxial with the pivot of the blank holder traversing lever and having a follower engaging the cam groove, a second lever, a link connecting the levers, an upper lever member pivotally connected to the second 10 lever and connected to the pointer member, a tension device normally tending to maintain said second lever and the upper lever member in alignment and which exerts a force on the upper lever member less than 15 that exerted thereon by the pointer member due to the effect of the weight means acting on the pointer member when a blank is brought in contact with the latter, whereupon the blank holder, the blank, and the pointer 20 member move together; the tension means being overcome and the pointer member moving in advance of the second lever, and an adjustable member carried by the blank holder traversing means and arranged to contact 25 with the first lever to limit motion of the pointer member in advance of the second lever, whereupon the tension means becomes the sole means to cause the pointer member to be advanced as the blank is being pointed 30 and the weight means being effective to cause the blank holder traversing means to follow the motion of the first lever until the weight means becomes ineffective; means for opening and closing the die including an operating 35 member, a lever connected to the operating member, an abutment carried by the rod of the blank holder and arranged to contact with the lever during the extreme outward portion of the outward motion of the blank holder 40 to render the operating member effective to close the die, a link connected to the lever, and means carried by the first lever of the pointer member traversing means and cooperating with said link to render the operating 45 member effective to open the die when said first lever occupies a predetermined position.
6. In a bolt threading machine, in combination, a rotatable die, a movable bolt holding member, a lever for operating said bolt holding member, a cam for moving said lever in one direction, a gravity operated lever for moving said first lever in the opposite direction, and an adjustable stop for limiting the 50 downward movement of said gravity operated lever.
7. In a threading and pointing machine, the combination of a pointer member and mechanism for traversing the pointer member 55 including a cam, a lever operated by the cam, a link pivoted to the lever and connected to the pointer member, and resilient means adapted to yieldingly resist rearward movement of the link with respect to the lever, whereby the pointer member may be moved 70 in one direction in advance of the lever against the action of the resilient means.
8. In a threading and pointing machine, the combination of a pointer member; mechanism for traversing the pointer member including a cam, a lever operated by the cam, a link pivoted to the lever and connected to the pointer member, and resilient means adapted to yieldingly resist rearward movement of the link with respect to the lever, 75 whereby the pointer member may be moved in one direction in advance of the lever; and adjustable means for limiting the movement of the pointer member in advance of said lever against the action of the resilient means. 80
9. In a threading and pointing machine, the combination of a blank holder; a pointer member; means for traversing the blank holder including power-operated means for moving the blank holder outwardly and biasing means for moving it inwardly; means for traversing the pointer member including power-operated mechanism and a yieldable connection between said mechanism and the pointer member, the biasing means of said 90 blank holder being effective to overcome the yieldable connection when a blank contacts with the pointer member to cause movement of the latter in advance of the power-operated mechanism; and adjustable means carried by 95 the blank holder and cooperating with the power-operated mechanism of the pointer member traversing means to limit the advance movement of the pointer member. 100
10. In a threading and pointing machine, the combination of a pointer member and mechanism for traversing the pointer member including a cam, a first lever having a follower cooperating with the cam, a second lever, a link connecting the levers, an outer lever member pivotally connected to the second lever and connected to the pointer member, and tension means cooperating with the second lever and with the outer lever member 110 to maintain the second lever and the outer lever member in alignment but permitting of the second lever member being moved in one direction by the pointer member in advance of the second lever. 115
11. In a threading and pointing machine, the combination of a threading die, a pointer member, means for opening and closing the threading die, a cam, a first lever having a follower engaging the cam, a second lever, a link connecting the levers, yieldable connecting means between the second lever and the pointer member, whereby the latter may be moved to a greater extent in one direction than would be permitted by the connecting levers and the cam, and means operated by the 120
12. In a threading and pointing machine, the combination of a pointer member, a cam, a first lever having a follower engaging the cam, a second lever, a link connecting the levers, yieldable connecting means between the second lever and the pointer member, whereby the latter may be moved to a greater extent in one direction than would be permitted by the connecting levers and the cam, and means operated by the 125
13. In a threading and pointing machine, the combination of a pointer member, a cam, a first lever having a follower engaging the cam, a second lever, a link connecting the levers, yieldable connecting means between the second lever and the pointer member, whereby the latter may be moved to a greater extent in one direction than would be permitted by the connecting levers and the cam, and means operated by the 130

first lever at a predetermined position thereof for moving the opening and closing means of the die in an opening direction.

12. In a threading and pointing machine, 5 the combination of a threading die, a pointer member, a blank holder, an operating shaft, peripheral and face cams on the operating shaft, the peripheral cam having a cam portion of limited arcuate extent and the face 10 cam having a lateral cam groove, a bell crank lever having upwardly extending and substantially horizontally extending arms, the upwardly extending arm being acted upon by the peripheral cam, a rod connected to the 15 blank holder and pivotally connected to the upwardly extending arm, a lever having its pivot coaxial with the pivot of the bell crank lever, overlying the substantially horizontally extending arm of the bell crank 20 lever, and having a weight secured thereto, adjustable means for limiting downward movement of the second lever and its weight, a third lever having its pivot coaxial with the pivot of the bell crank lever and having a 25 follower fitting the cam groove of the face cam, a fourth lever, a link connecting the third and fourth levers, a yieldable connection between the fourth lever and the pointer member, adjustable abutment means carried 30 by the rod connected to the blank holder and adapted to contact with the third lever, whereupon the bell crank lever and the third lever move together as determined by the cam groove until downward movement of the sec- 35 ond lever and of its weight is limited, an operating member for opening and closing the threading die, and means carried by the rod of the blank holder and by the third lever to render said operating member effective, re- 40 spectively, to close the die and to open the die.

13. In a threading and pointing machine, the combination of a threading die, a pointer, a blank holder, means for traversing the blank holder including a lever, means for 45 traversing the pointer including a lever, and means for moving the levers in synchronism after the pointing operation, said levers being of different lengths whereby the pointer moves more rapidly than the blank holder.

50 14. In a threading and pointing machine, the combination of a threading tool, a pointing device longitudinally movable relative to the threading tool, means for rotating the

threading tool and pointing device, a blank holder, means for positively feeding the 55 blank holder toward the pointing device to operatively engage the blank and pointing device, means for interrupting the feeding movement of the blank holder, means for continuing the positive feeding of the 60 blank holder following the pointing operation to bring the blank into full operative engagement with the threading tool, and means for interrupting the positive feed of the blank holder to permit the further feed of the 65 blank holder to be effected by the action of the threading tool on the blank.

15. In a threading and pointing machine, the combination of a threading tool, a pointing device concentrically disposed and longitudinally movable relative to the threading tool, means for rotating the threading tool and pointing device, a blank holder, means for positively feeding the blank holder toward the pointing device to operatively engage the blank and pointing device, means for interrupting the feeding movement of the blank holder, means for moving the pointing device rearwardly after the pointing operation, means for continuing the positive feeding of the blank holder following the pointing operation to bring the blank into full operative engagement with the threading tool, and means for interrupting the positive feeding of the blank holder to permit the further feed 80 of the blank holder to be effected by the action of the threading tool on the blank.

16. In a threading and pointing machine, the combination of a threading tool, a pointing device longitudinally movable relative to 90 the tool, means for positively reciprocating the pointing device relative to the threading tool, resilient means operatively interposed between the reciprocating means and the pointer to yieldingly resist rearward movement of the pointing device, a blank holder, means for feeding the blank holder to engage the blank with the pointing device and move the pointing device rearwardly against the action of the resilient means, and means for interrupting the feed of the blank holder to permit the resilient means to move the pointing device forwardly for pointing the blank.

In testimony whereof I hereunto affix my signature.

JAMES A. KINNEY.
